UNITED STATES PATENT OFFICE.

HENRY G. HALL, OF SHELBY, NORTH CAROLINA.

ART OF MANUFACTURING BANDS FOR SPINNING AND TWISTING MACHINES AND MACHINE THEREFOR.

SPECIFICATION forming part of Letters Patent No. 440,476, dated November 11, 1890.

Application filed January 10, 1890. Serial No. 336,544. (No model.)

To all whom it may concern:

Be it known that I, HENRY G. HALL, of Shelby, in the county of Cleveland and State of North Carolina, have invented a new and useful Improvement in the Art of Manufacturing Bands for Spinning and Twisting Machines and Machines Therefor, of which the following is a full, clear, and exact description.

10 Heretofore in the manufacture of bands—such as are used for driving spindles of spinning and twisting frames—the same have been made in what are called "loop-banding machines," in which two live-spindles and one 15 sliding dead-spindle are used, each provided with a hook for carrying the cord or strands of which the band is composed. The two hooked live-spindles are arranged at one end of the machine and the sliding hooked dead-spindle at or near the other end thereof. One end of what may be termed the "cord," 20 but which consists of continuous loose strands, is tied at its one end onto the hook of the one live-spindle. Then said cord is 25 passed around the hook of the dead-spindle and returned or brought back and secured at its other end to the hook of the other live-spindle. The live-spindles are then rotated to put the twist into the strands, which, by shortening the cord, causes the dead-spindle that 30 is held back by a weight to slide forward its extreme limit. The machine is then stopped and the one end of the cord lifted from off the one live-spindle and transferred to the 35 other live-spindle, which continues to carry the opposite end of the cord, and which is then revolved in an opposite direction to that in which it previously moved for the purpose of twisting the two lines of cord together to 40 form the band. This at first causes the band to lengthen by reason of the reverse twist first given to the strands, the dead-spindle then sliding back a given distance; but as the two lengths of cord are continued to be twisted 45 together the band begins to shorten, the dead-spindle sliding forward again a certain distance with or as drawn by the band. The band is then removed from the machine and thrown across a frame, when all the twist 50 which was given it as it shortened and the dead-spindle moved forward, as last described,

runs out or is lost. A band thus made lacks in both durability and efficiency, owing to its not being stretched and its liability when in use to slacken, thereby causing much waste. 55 All this I obviate by treating the band as a belt and stretching it after it has shortened by the twisting of the two lengths of cord together until a large amount of extra twist has been put in and afterward subjecting it while 60 so stretched to tension for a sufficient length of time for the final twist to become set. A band thus made will be thoroughly stretched before it is applied to its work, will not be liable to slacken when in use, thus preventing 65 "soft bobbins," and will largely exceed in durability bands as ordinarily made.

Reference is to be had to the accompanying drawings, forming a part of this specification, in which similar letters of reference indicate 70 corresponding parts in all the figures.

Figure 1 represents a plan of a band making or twisting and stretching machine embodying my invention. Fig. 2 is a side elevation of the same. Fig. 3 is a further side 75 elevation, in part, showing the dead-spindle in position when forced back. Fig. 4 is a transverse section upon the irregular line xx in Fig. 3. Fig. 5 is a plan view of the hook end of the dead-spindle; and Fig. 6 is a longitudinal sectional view of a screw-adjusting means used on the holder, which keeps the band at its stretch until the final twist put in the band has become set.

A is the dead-spindle, having a hook b on 85 its forward end and fitted to slide back and forth through standards $c c$, mounted on the bed B of the main frame.

C are the hooked live-spindles, fitted to rotate in bearings d at the opposite end of the 90 bed, and which may be driven by a band (not shown) passing over a pulley e and whirls $f f$. This, together with the attachment of a cord g to the rear end of the dead-spindle and passing over a pulley h on the main frame, and 95 having a weight i attached to it to draw the dead-spindle back, is or may be the same as in the ordinary loop-banding machines hereinbefore referred to. The hook b on the dead-spindle, however, is grooved at its forward 100 end, as at k , for a purpose that will be hereinafter described. A dog l is secured to the

dead-spindle, the uses of which will also be hereinafter explained.

The operation up to a certain point is the same as that of an ordinary loop-banding machine. Thus the doubled line of strands, yarns, or rovings, or what has been termed the "cord," as shown in Fig. 1, is first passed round the hook *b* on the dead-spindle and its two ends fastened, respectively, to the hooks 5 of the live-spindle *C C*, and the latter rotated to put the twist into the strands, which shortens the cord and causes the dead-spindle *A* to move forward to its extreme limit, as shown in Fig. 1. The machine being stopped, one end 10 of the cord is removed from the one live-spindle *C* and hitched onto the other live-spindle *C*, which then carries both ends of the cord, after which said live-spindle is revolved in an opposite direction for the purpose of twisting the two lines of cord together to form the band *D*, and which first causes said band to lengthen and the dead-spindle *A* to move a given distance back, and so that the dog *l* will travel from its extreme forward position 15 (shown in Fig. 1) to the position shown for it by dotted lines in Fig. 2, after which the band, continuing to twist, shortens, causing the dead-spindle to be moved forward until its dog *l* assumes the position shown for it by 20 full lines in Fig. 2. This operation having been completed, the novel feature of my invention now begins. Thus, instead of taking off the band when the dog *l* reacts or reaches in the shortening of the band the position 25 shown for it by full lines in Fig. 2, and when the band has heretofore been called finished, I force said dog and dead-spindle on which it is adjustably held by a set-screw *l*, to suit different lengths of band, back, more or less, say 30 to the extreme length of its backward movement, as shown by full lines in Fig. 3, or even less, and thereby stretch said band. In this stretched condition I remove the band to a tension-holder, and keep it there until the final 35 twist has become set, and thereby increase its usefulness and very largely so its durability, and make it so that it will not be liable to get slack or stretch when in use, thus avoiding the many evils consequent thereon. The 40 means shown for doing this consists, in the first place, of a hand-lever *E*, which as it is moved in direction of the arrow *y* moves the dog *l*, with its attached dead-spindle, back from the position shown by full lines in Fig. 45 2, to the position, say, shown for it in Fig. 3, said lever *E* thus moving said dog by means of a connecting-rod *m*, attached to a crank *m'* on its rock-shaft and at its other end to a crank *n* upon a rock-shaft *o*, that carries an 50 arm *r*, provided with a roller, which bears against the dog *l*. This stretches the band, as described, and partly sets the twist; but before thus stretching the band I first remove by hand the one-looped end of it from the 55 live-spindle *C*, on which it is secured, and engage said end with a toothed disk *G* on a tension-holder *H*, and then move the dog *l* back

to give the stretch, as described, until the hook *b* on the dead-spindle just passes over a second toothed disk *G'*, which is then moved 60 up to cause a tooth on it to pass up the groove *k* in the hook *b* and to engage with the loop on the end of the band on said hook and to lift such end of the band from the hook *b*, after which said disk *G'* is lowered again to 65 its normal position and the stretched band is allowed to remain on the disks *G G'* some few hours, more or less, until the extra twist given to it is fully set.

The holder *H* consists, mainly, of a length of 70 gas pipe or tube *a'*, resting in an open bearing *b'* at each end, and the toothed disks *G G'*, carried by said tube. These disks are adjustable on or along said tube to suit different lengths of band by fitting them to slide 75 thereon and adjusting and holding them in position when adjusted by means of screw-bolts *c'* within each end of the tube *a'*, provided with keys *d'* at their forward ends, arranged to pass through slots *e'* in the tube and 80 bearing against the hubs of the disks, and nuts *f'*, fitting the screw-threads on the back or outer ends of the bolts *c'*.

The end of the tube *a'*, carrying the disk *G'*, is raised to cause the said disk to lift the band 85 from the hook *b* of the dead-spindle, as hereinbefore described, by suitably pressing on a lever *I*, which may be operated by the knee and is arranged to bear on the under side of that end of the tube *a'* which carries the disk 90 *G'*, thus raising said end of the tube and disk *G'* along with it, as required. By screwing up the nuts *f'* they will also stretch the band if put on too slack, and the disks *G G'* have 95 their teeth so closely arranged around their perimeters that they will serve to hold a large number of bands under stretch at the same time. The same band-holder *H* may also be used for stretching mule-spindle bands, one 100 end of which may be fastened to a tooth and the cord or band woven backward and forward on the disks, after which the nuts *f'* may be screwed up, thereby giving a powerful 105 stretch to the band and dispensing with the appliances now used in cotton and woolen 110 mills for taking up the slack of mule-banding.

It should here be observed that the pith of the invention, as here described, consists in holding the band stretched after it has been 115 fully twisted until the final twist put therein in the operation of twisting, and during which the band is shortened, has become set, irrespective of the means by which this is done—as, for instance, whether by a separate holder or otherwise, or, if desired, by transferring 120 the stretched band to the spindle direct it is 125 designed to drive.

Having thus fully described my invention, I claim as new and desire to secure by Letters Patent—

1. The method herein described of making cord-like bands suitable for spinning and twisting machines, which consists in first twisting the yarns or rovings together in independ-

ent cord-like lengths, then twisting in a reverse direction said cord-like lengths about each other, and then after the final twist has been put in the band, as described, forcibly in combination with the sliding dead-spindle A, having a hook b, and either hooked live-spindle C, essentially as and for the purpose 40 herein set forth.

5 stretching said band and holding it under tension till the final twist has been set, substantially as specified.

2. In machines for making cord-like bands for spinning and twisting machines, the combination, with the rotating live-spindles and with the sliding dead-spindle thereof, of means adapted to stretch the band after the two cord-like lengths of it have been twisted together in a reverse direction to that in which said lengths were independently twisted, substantially as herein set forth.

3. In a machine for making and stretching bands of the character herein described, the combination, with the two live-spindles C and 20 opposite sliding dead-spindle A, of the dog l on said dead-spindle and a hand-lever mechanism adapted to force said dog and dead-spindle back, essentially as and for the purposes herein set forth.

25 4. In a machine for making and stretching bands of the character herein described, the combination, with the two live-spindles, the sliding dead-spindle of the machine, and a hand mechanism adapted to force said dead-spindle back and to stretch the twisted band, of a separate holder adapted to receive the twisted and stretched band and to hold it under tension, substantially as specified.

30

35 5. In a machine for making and stretching bands of the character herein described, the holder H, provided with two opposite end disks G G', having teeth on their perimeters,

in combination with the sliding dead-spindle A, having a hook *b*, and either hooked live-spindle C, essentially as and for the purpose herein set forth.

6. In a machine of the character herein described, the combination, with the hook *b* on the sliding dead-spindle *A*, provided with a groove *k* on its exterior, of the holder *H*, having toothed disks *G G'* and supported so as to be capable of being raised, and means for raising the same and adapted to project a tooth of one of said disks up through or within the groove *k* in the hook *b*, substantially as 50 and for the purpose herein specified. 45

and for the purposes herein specified.

7. In a machine for making and stretching bands of the character herein described, the combination, with the sliding dead-spindle A, live-spindles C C, and with a hand mechanism adapted to force said dead-spindle back and to stretch the band after it has been twisted, of the band-holder H, provided with toothed disks G G', near its opposite ends made adjustable toward or from each other, essentially as and for the purposes herein set forth. 55 60

8. In a machine of the character herein described, the band-holder H, consisting of a tubular spindle a', having longitudinal slots e' e' near its opposite ends, the adjustable toothed disks G G', the screws or screw-bolts c', having keys d', arranged to pass out through said slots, and the nuts f' on the outer ends of said bolts, substantially as specified. 65
